US00D818485S

(12) **United States Design Patent** (10) **Patent No.:** **US D818,485 S**
Boot et al. (45) **Date of Patent:** **** May 22, 2018**

(54) **DISPLAY SCREEN OR PORTION THEREOF
WITH GRAPHICAL USER INTERFACE**

(71) Applicant: **Sanford, L.P.**, Downers Grove, IL (US)

(72) Inventors: **Bram Boot**, Borgerhout (BE); **Stephen Spencer**, Atlanta, GA (US)

(73) Assignee: **Sanford, L.P.**, Downers Grove, IL (US)

(***) Term: **15 Years**

(21) Appl. No.: **29/597,589**

(22) Filed: **Mar. 17, 2017**

Related U.S. Application Data

(63) Continuation of application No. 29/477,392, filed on Dec. 20, 2013, now Pat. No. Des. 784,359.
